UNITED STATES PATENT OFFICE

101,088

DESIGN FOR A COMBINED SAFETY RAZOR BLADE RECEPTACLE AND HONER OR SIMILAR ARTICLE

Lionel Plante, Newark, N. J.

Application July 3, 1936, Serial No. 63,634

Term of patent 7 years

To all whom it may concern:

Be it known that Lionel Plante, citizen of the Dominion of Canada and resident of New Jersey, in the city of Newark and State of New Jersey, has invented a new, original, and ornamental Design for a Combined Safety Razor Blade Receptacle and Honer or Similar Article, of which the following is a specification, reference being had to the accompanying drawing, forming part thereof, in which,

Fig. 1 is a top perspective view of a combined

safety razor blade receptacle and honer, or similar article;

Fig. 2 is an end elevational view thereof;

Fig. 3 is a side elevational view; and

Fig. 4 is a bottom perspective view thereof.

I claim:

The ornamental design for a combined safety razor blade receptacle and honer or similar article, substantially as shown.

Dated: New York city, June 30th, 1936.

LIONEL PLANTE.
